CONTAINER

Gordon R. Sharpe, Vancouver, British Columbia,
Canada

Application March 15, 1937, Serial No. 131,083

6 Claims. (Cl. 229—6)

This invention relates to a container particularly adapted for the shipment of baby chicks.

An object of the present invention is the provision of a container formed from a single blank.

5 Another object is the provision of a container which may be assembled without the use of glue, staples or the like.

10 A further object is the provision of containers formed to allow for the circulation of air therearound and therethrough when piled side by side and on top of one another during shipment or storage.

15 Another object is the provision of a container of very simple construction which may be very easily manufactured and assembled.

There are a number of containers for the shipment of baby chicks now on the market but the majority of these are made up of a number of pieces which have to be glued or stapled together.

20 Another objection to all known types of containers for this purpose is that they either do not allow for the circulation of air therearound when piled up during shipment or they allow for the circulation of air therearound only but do not provide for ensuring circulation therethrough.

This invention overcomes these difficulties by providing a container formed from a single blank the sides, ends and covers of which are interlocking thus eliminating the necessity of glue, 25 staples or other fastenings. The top of this container is so formed that when one container is placed upon another, air circulating therearound must pass through the top into the container and out again.

30 The present invention consists essentially of a blank so cut and scored that it may be folded with its sides, ends and covers interlocking to form a container having means for allowing air to circulate therearound and therethrough when the containers are stacked for shipment as more 35 fully described in the following specification and illustrated in the accompanying drawing, in which.

Figure 1 is a plan view of the blank cut and 40 scored ready for folding.

Figure 2 is a longitudinal section through the folded container.

Figure 3 is a transverse section through the folded container.

50 Figure 4 is a plan view of the container with the covers removed, and

Figure 5 is a perspective view of the container.

Referring more particularly to the drawing,

55 Figure 1 illustrates a blank A, formed of corrugated or light pulp board which is cut and scored

in such a way that it may be folded to form the container B. The blank A is formed with a central portion 10 which constitutes the bottom of the container. The blank is scored at 11 and 12 to form the sides 13 and 14 each of which is 5 scored at 15 and 16 to form flaps 17 and 18 at each end thereof. The scored lines 15 and 16 slant towards each other so that the flaps 17 and 18 are formed at an angle to the sides the purpose of which will appear later. The sides 13 and 10 14 are further scored at 19 and 20 to form covers 21 and 22. The cover 22 is provided with tongues 23 and 24 along its outer edge while the cover 21 is provided with a flap 25 along its outer edge and slots 26 and 27 adapted to receive the tongues 23 15 and 24 when the container is assembled. The sides 13 and 14 are provided with slots 28 and 29 centrally thereof which extend inwardly from the respective scored lines 19 and 20 and terminate at a point adjacent the scored lines 11 and 20 25. The blank A is scored at 30 and 31 to form the ends 32 and 33 which are further scored at 34 and 35 to form flaps 36 and 37. The flaps 36 and 37 are approximately the same width as the ends 32 and 33 while said ends are wider 30 than the sides 13 and 14. The sides of the ends 32 and 33 converge from the scored lines 30 and 31 towards the scored lines 34 and 35 and the sides of the flaps 36 and 37 diverge from said 35 scored lines 34 and 35 towards the outer edges of the flaps. Slots 38 and 39 are provided, the slot 38 extending across the scored line 34 part way into the end 32 and the flap 36 and the slot 39 extending across the scored line 35 part way into the end 33 and the flap 37. The sides, ends, covers and all the flaps with the exception of the flap 25 are provided with ventilation openings 40 and the flaps 36 and 37 are provided with recesses 41 and 42 in their outer edges.

The above described blank is folded to form the 40 container in the following manner:

The sides 13 and 14 are folded upward relative to the bottom 10 along the scored lines 11 and 12 and the flaps 17 and 18 are folded inwardly along the scored lines 15 and 16 at right 45 angles to the sides. When the flaps 17 and 18 are folded in this manner with their lower edges resting on the bottom 10, the sides 13 and 14 slope inwardly owing to the fact that said flaps are formed at an angle to the sides. Next, the 50 ends 32 and 33 are folded upwardly along the scored lines 30 and 31 until they rest against the flaps 17 and 18 and since the scored lines 15 and 16 slant towards each other, said flaps and, consequently, the ends slope inwardly. Then the 55

flaps 38 and 37 are folded over and against the inside surfaces of the flaps 17 and 18 thus locking the latter and the sides in place. If desired, the container may be divided into two compartments 5 by means of a partition 43 extending transversely of the container the upper corners of which project into the slots 28 and 29 which are situated centrally of the upper edges of the sides, the slope of the latter making this possible. If it is necessary to divide the container into four compartments, an additional partition 44 may be used which extends longitudinally of the container with the upper corners of its ends projecting into the slots 38 and 39 which are situated centrally 10 of the upper edges of the ends of the container. The container is now ready for use.

In order to close the container, first the cover 21 is folded inwardly along the scored line 19 and then the flap 25 is folded downwardly with 20 its extensions 45 projecting into the slots 38 and 39. This locks the cover 21 in place. The cover 22 is folded inwardly along the scored line 20 and the tongues 23 and 24 are bent downwardly and inserted into the slots 26 and 27 of the cover 21. 25 This locks the cover 22 in closed position. The bottoms of the slots 38 and 39 lie above the tops of the sides 13 and 14 when the container is folded so that when the extensions 45 of the flap 25 lie therein the cover 21 slants upwardly from the 30 side 13 and consequently the cover 22 slants upwardly from the side 14 resulting in the container having a peaked roof.

As stated above in describing the blank A, the ends are wider than the sides so that when the 35 blank is folded the ends are higher than said sides. With this construction when one container is stacked upon another, an air space is left therebetween. The peak of the peaked roof of the container, however, almost reaches the tops 40 of the ends. In this way air circulating between the stacked containers must enter the ventilation openings of one cover, pass through the container and out through the openings of the other cover. The peaked roof also leaves an air space above 45 the partitions 43 and 44 so that the air may circulate to all parts of the container. The sloping side and ends of the container allow for the circulation of air around the containers when they are piled side by side and, of course, the ventilation 50 openings in said sides and ends further aid the circulation of air through the container.

The flaps 38 and 37 not only lock the sides and the ends of the container together but they act as a reinforcement for said ends which bear the 55 load when the containers are stacked upon each other.

From the above it will readily be seen that a container has been provided which may be formed from a blank scored to form sides, ends and covers which are interlocking when folded together, said container including means for ensuring the circulation of air therethrough and said container being of very simple construction and very 60 easy to assemble without glue, staples or the like.

Various modifications may be made in this invention without departing from the spirit thereof or the scope of the claims, and therefore the exact forms shown are to be taken as illustrative only and not in a limiting sense, and it is desired 65 that only such limitations shall be placed thereon as are disclosed in the prior art or are set forth in the accompanying claims.

What I claim as my invention is:

1. A container formed from a blank scored to 70 form sides and ends therefor, flaps formed at an

angle to the ends of the sides, said flaps being adapted to be folded inwardly at right angles to the sides when the latter are folded upwardly, the angle of said flaps relative to the sides permitting the sides to slope inwardly, means formed with 5 the ends adapted to interlock the sides and ends when said ends are folded upwardly, covers formed with the sides adapted to interlock when folded inwardly to form a roof for the container, means formed with the covers adapted to co-operate 10 with the ends to hold the covers, when folded, in peaked formation and a plurality of openings in the blank for permitting air to circulate through the container when assembled.

2. A container formed from a blank scored to 15 form sides and ends therefor, flaps formed at an angle to the ends of the sides, said flaps being adapted to be folded inwardly at right angles to the sides when the latter are folded upwardly, the angle of said flaps relative to the sides permitting 20 the sides to slope inwardly, flaps formed with the ends adapted to be folded over the first mentioned flaps when said ends are folded upwardly to interlock the sides and ends, covers formed with 25 the sides, one cover having slots and the other having tongues adapted to fit into said slots when the covers are folded inwardly to interlock said covers to form a roof for the container, means formed with the covers adapted to co-operate 30 with the ends to hold the covers, when folded, in peaked formation and a plurality of openings in the blank for permitting air to circulate through the container when assembled.

3. A container formed from a blank scored to 35 form sides and ends therefor, flaps formed at an angle to the ends of the sides, said flaps being adapted to be folded inwardly at right angles to the sides when the latter are folded upwardly, the angle of said flaps relative to the sides permitting the sides to slope inwardly, flaps formed 40 with the ends adapted to be folded over the first mentioned flaps when the ends are folded upwardly to interlock the sides and ends, said ends and associated flaps being higher than the sides, each end and flap having a slot in the upper edge 45 thereof the bottom of which lies above the upper edge of the sides, covers formed with the sides, one cover having slots therein and a flap at its outer edge with extensions adapted to project into the slots of the ends when the cover is folded 50 inwardly and the other cover having tongues adapted to fit into the slots of the first cover when the former is folded inwardly to interlock said covers to form a peaked roof for the container and a plurality of openings in the blank 55 for permitting air to circulate through the container when assembled.

4. A container having sides and ends adapted to slope inwardly, said ends being higher than the sides, flaps formed with the sides folded inwardly inside the ends, flaps formed with the ends adapted to be folded over the first mentioned flaps to interlock the sides and ends, covers formed integral with the sides, one cover having slots and the other having tongues adapted to fit into said slots when the covers are closed to interlock said covers to form a roof for the container, means formed with one of the covers adapted to co-operate with the ends to hold said covers, when folded, in peaked formation and a 70 plurality of openings in the sides, ends and covers for permitting air to circulate through the container.

5. A container having inwardly sloping sides and re-inforced ends adapted to interlock there- 75

with, said ends being higher than the sides and having slots centrally of their upper edges, covers formed integral with the sides, one cover having slots and a flap at its outer edge with extensions at each end thereof adapted to project into the end slots when the cover is closed and the other cover having tongues formed on its outer edge adapted to fit into the slots of the first cover when the former is closed to interlock said covers to form a peaked roof for the container and a plurality of openings in the sides, ends and covers for permitting air to circulate through the container.

6. A container having inwardly sloping sides, flaps formed with the sides adapted to be folded inwardly at right angles thereto, inwardly sloping, re-inforced ends adapted to interlock with said flaps, said ends being higher than the sides

and having slots centrally of their upper edges, said sides also having slots centrally of their upper edges, partitions extending transversely and longitudinally of the container having their upper corners projecting into slots of the sides and the slots of the ends respectively, covers formed integral with the sides, one cover having slots and a flap at its outer edge with extensions at each end thereof adapted to project into the end slots when the cover is closed and the other cover having tongues formed on its outer edge adapted to fit into the slots of the first cover when the former is closed to interlock said covers to form a peaked roof for the container and a plurality of openings in the sides, ends and covers for permitting air to circulate through the container.
